UNITED STATES PATENT OFFICE.

ERNEST S. NIESTRADT, OF DENVER, COLORADO, ASSIGNOR TO THE NORTHWESTERN TERRA COTTA COMPANY, OF CHICAGO, ILLINOIS, A CORPORATION OF ILLINOIS.

METHOD AND MEANS FOR MAKING MOLDS FOR BUILDING BLOCKS AND THE LIKE.

Application filed September 28, 1926. Serial No. 138,233.

This invention relates to a method and apparatus for forming building blocks of plastic material and its principal object resides in the provision of a simple manner 5 and means for making a mold in which a building block may be formed without the use of a model.

My invention is particularly useful in 10 making building blocks of ornamental design which in prior practice could be formed only by first making a model which in size and form was identical to the blocks to be formed, and then making a mold by use of the model in which the building blocks were 15 subsequently cast.

The method of forming ornamentally faced building blocks according to the present invention, eliminates the production of an original or model in making a mold of 20 the required design, and it therefore involves a considerable saving in labor, time and money while at the same time avoiding the employment of skilled artists heretofore required to carve or otherwise produce the 25 models.

In the practise of my improved method of forming the molds, use is made of simple devices and parts which are used and arranged in a manner peculiar to my invention 30 and these devices and parts in their cooperative relation in which they are placed in the successive steps of the method have been shown in the accompanying drawings.

It is to be understood that the form, shape 35 and arrangement of the parts must necessarily be varied in accordance with the type and form of the building blocks to be produced and that the drawings are merely an exemplification of the means employed in the method as will hereinafter be described.

In the drawings in which like characters 40 of reference designate corresponding parts throughout the several views,

Figure 1 represents a plan view of a 45 knock-down mold or form used in producing the side-members of the mold in which the building blocks are to be cast,

Figure 2, a section taken on the line 2—2 50 Figure 1,

Figure 3, a section along the line 3—3 Figure 1,

Figure 4, a fragmentary section similar to Figure 2, showing a modification of the

form and arrangement of the parts of the 55 mold,

Figure 5, a fragmentary perspective view of two adjoining parts of the form illustrated in Figure 1,

Figure 6, a perspective view of one of the mold-members produced in the form shown in Figure 1,

Figure 7, a perspective view illustrating the method of forming the base-member of the mold by means of a profile templet,

Figure 8, a perspective view of a part of the templet,

Figure 9, a plan view of a knock down form employed in making the base member of a mold for forming plain-faced building blocks,

Figure 19, a fragmentary section on the line 19—19 Figure 16, drawn to an enlarged scale,

Figure 20, a plan-view of the completed mold,

Figure 21, a section along the line 21—21, 95 Figure 20,

Figure 22, a section taken on the line 22—22, Figure 20, and

Figure 23, a perspective view of the building block produced in the mold depicted in Figure 20.

Referring first to Figures 1 to 6 of the drawings, the side-members 5 of the mold are made in a form made up of parts assembled upon a work bench, slab or other plain surface. The parts used in making

the form, are of a stock pattern and being made in different lengths or widths they may be assembled for forming mold-members of various sizes.

5 The distinctive feature of the side members 5 of the mold to be formed are a tongue 6 along an edge thereof, and correspondingly formed grooves 7 in a face of the same, the tongue and grooves being employed in 10 assembling the side-members with the other members of the mold as will hereinafter be explained.

The parts of which the form is made are of two kinds, namely flat strips 8 provided 15 with ridges 9 of V-shaped section to produce the grooves of the member 5, and bars 10 provided with V-shaped grooves 12 to provide the tongues 6 of the members. The bars are flat on their sides opposite to their 20 grooved sides so that in a reversed position they may form the flat ends of the mold-members. This has been illustrated in Figures 1 to 3 in which three of the bars are placed with their flat sides within the form 25 and the fourth one has its grooved side inside the same.

The bars are furthermore recessed at their underside in conformity with the ridged surfaces of the flat strips 8, as best shown at 30 13 in Figure 5 so that they may be placed over the strips while maintaining their contact with the plain surface on which the parts of the form are assembled.

The various parts of the form are beveled as indicated at 14 and 15 to form a panel on the face of the members which produces correspondingly formed rebates in the 35 sides of the molded block.

It will be observed that the parts of the 40 form may be placed at any distance apart within the limits of their lengths to make mold-members of different dimensions and proportions.

The parts of the form are preferably 45 made of metal and they may be hollowed to reduce weight and expense of material. The hollow construction of the parts has not been shown in the drawings but it can be readily understood without further illustration.

The side members 5 of the mold are cast 50 in the form of plaster of Paris or other plastic material, it being apparent that after the material has hardened in place, the form 55 base or matrix-member 16 of the mold is parts from the molded article.

Referring now to Figures 7 and 8, the base or matrix-member 16 of the mold is 60 made of a mass of soft plaster of Paris or other plastic material placed on a work-bench, slab or other plain surface by drawing a profile templet 17 across its upper surface. The templet may be made of a body part 18 of wood or other suitable material and edge-plates 19 and 20 of metal 65

which are cut in the form of the required ornamental surface of the building block.

The plates are made in three end-to-end adjoining sections which are fastened to the body member by means of nails, screws or 70 rivets and extend below the lower edge thereof.

The middle section is cut in the form of the ornamental contour of the building blocks to be formed in the mold and the 75 end-sections are cut with ridges to form grooves 21 along the side-edges of the base-member of the mold, which register with the tongues 6 of the side members 7 of the same.

The mass of plastic material of which the 80 base member of the mold is formed hardens while the templet is drawn across its surface and after it has completely hardened, its ends are sawed off to the required length.

The member is subsequently chiseled adjacent the ends of its upper surface to provide grooves 22 and 23 and pits 24, which together form the so-called "jagger-holes" 85 which lock the end-members 25 of the mold in place upon the base-member of the same.

In the production of plain-faced building blocks without ornamental surface the base block may be made in a manner similar to that employed in the production of the side-members, as illustrated in Figures 9 to 11 90 in which four ridged strips 26 and four bars 27 formed similarly to the strips and bars of the form illustrated in Figure 1, are assembled in right angular formation upon a work bench or other level surface. The 95 four strips form grooves along the margin of the base-member to register with corresponding tongues on the side members and end members of the same, and the beveled edges of the strips form a panel between the 100 grooves.

It will be noted that in this form all the 105 bars are placed with their plain surfaces innermost inasmuch as no tongues or grooves are required at the edges of the base-member. To produce a rebate of greater depth the strips 26 may be widened and the bars placed on their extensions 26a as illustrated in Figure 4.

Having thus obtained the base member and the side members of the mold, the end-members 25 are produced by casting in a form of which the case and side members are parts. This step in the method of forming the mold is illustrated in Figures 12 to 15.

The side members are placed on the base member in the proper position with their tongues in the grooves 21 as clearly shown 120 in Figure 14. The ends of the mold are closed by upright boards or plates 28 and at distances from these boards or plates, equal to the desired thickness of the end members of the mold, the space of the mold 125 between its side member is divided by metal partitions 29.

The partitions, shown in detail in Figures 16 to 18 consist of three plates 30 and 31, the outer ones of which are slidably connected with the middle one by holding-
straps 32. The straps are loosely fastened at their centers to the middle plate by means of bolts 33 and the end plates 31 are slipped into the spaces between the straps and the plate to which they are attached and are thus held in place.

The middle plate 30 is oblong and in order that it may be used in two positions, it has been provided with two sets of straps 32 at right angles to each other.

The construction of the partitions as above described renders them extensible and contractible so that they may be used in molds of different widths and it is to be understood that in molds of lesser width the middle member of the partitions may be omitted and the side-members placed inlapping relation to each other.

The outer members of the partitions are provided at their outer edges with rectangular flanges 34 which in practice engage upon the inner faces of the side-members of the mold as shown in Figure 12. The flanges may be folded upon themselves for the purpose of securing the vertical legs of squares 35 which by engagement with the face of the base member of the mold adjacent the side members of the same, facilitate placing the partition in a true vertical position. The squares slide in the doubled flanges so that they may be adjusted to different forms of molds, and they aid in supporting the partitions in the mold and in holding them in position while the end pieces of the mold are being cast.

The side plates of the partitions are usually offset as indicated at 36 in the drawings for the purpose of forming panels which in the production of the building blocks form rebates in the ends thereof.

After the end-plates 28 and the partitions 29 have been placed in their proper positions relative to the base member and side members of the mold, to produce the forms in which the end-members of the mold are to be cast, the spaces 37 between the lower edges of the partitions and the face of the base plate are filled with clay or other suitable material, the inner faces of the forms are coated with a lacquer of soap and water or other material to prevent sticking, and plaster of Paris or other plastic material is poured into the forms and allowed to harden in place.

The end-members thus produced have of course the counterparts of the grooves in the ends of the side-members and the jagger-holes in the face of the base member so that they may be removed at will and replaced in their proper position relative to the other members of the mold. The coun-

terparts above referred to comprise, as illustrated in Figure 15, tongues 41, knobs 39 to occupy the pits 24, and tenons 38 and 40 which fit into the grooves 22 and 23.

The end pieces have panels 43 which produce rebates 42 in the ends of the building blocks cast in the mold as illustrated in Figure 23. The tongues and grooves, and the jagger holes and counterparts of the five members of the mold, lock them securely together and the mold may be used in the same manner as monolithic molds made by different methods, heretofore employed in the production of building blocks or other articles of terra cotta and other plastic material.

Having thus described my invention, what I claim and desire to secure by Letters Patent is:—

1. The method of making a mold for building blocks and the like, consisting in separately producing the base member and side members of the mold, and casting the end members of the mold in forms, of which the priorly produced members are parts, the members of the mold being provided with integral means for locking them in their relative positions.

2. In apparatus for making a mold for building blocks and the like, the combination with a base-member of the mold and opposite side-members of the same, of closing means for an end of the mold, and a removable partition spaced from said closing means.

3. In apparatus for making a mold for building blocks and the like, the combination with a base-member of the mold and opposite side-members of the same, of closing means for an end of the mold, and an extensible partition spaced from said closing means, in engagement with the side-members.

4. In apparatus for making a mold for building blocks and the like, the combination with a base member of the mold and opposite side-members of the same, of closing means for an end of the mold, and a partition spaced from said closing means and having flanges engaging with the side members.

5. In apparatus for making a mold for building blocks and the like, the combination with a base-member of the mold and opposite side-members of the same, of closing means for an end of the mold, a removable partition spaced from said closing means and having flanges engaging with the side members, and squares connected with said flanges to engage with the base-member.

6. In apparatus for making a mold for building blocks and the like, the combination with a base-member of the mold and opposite side-members of the same, of means for closing an end of the mold, and a parti-

tion spaced from said end and composed of slidably connected sections engaging the side-members.

7. In apparatus for making a mold for building blocks and the like, the combination with a base-member of the mold and opposite side-members of the same, of means for closing an end of the mold, and a partition spaced from said end and composed of 10 a middle section and outer sections slidably connected with the middle section and engaging the side members of the mold.

8. In apparatus for making a mold for building blocks and the like, the combination with a base-member of the mold and 15

opposite side-members of the same, of means for closing an end of the mold, and a partition spaced from said end between the side members and having laterally extending legs 20 engaging the base-member.

9. The method of making a mold for building blocks and the like, consisting in producing a base member, casting side members in forms apart from the base member, and casting end members in forms of which 25 the priorly produced members are parts.

In testimony whereof I have affixed my signature.

ERNEST S. NIESTRADT.
